UNITED STATES PATENT OFFICE.

MELVILLE M. UTTERBACK, OF CHELAN, WASHINGTON.

DISHWASHING MACHINE.

1,414,058.

Specification of Letters Patent. Patented Apr. 25, 1922.

Application filed September 17, 1921. Serial No. 501,504.

To all whom it may concern:

Be it known that I, MELVILLE M. UTTERBACK, a citizen of the United States, and resident of Chelan, county of Chelan, and 5 State of Washington, have invented a new and useful Dishwashing Machine, of which the following is a specification.

The present invention relates to improvements in dish washing machines and its object is to provide a machine of the character described that is particularly efficient 10 in washing dishes, needs only a limited supply of water, works with soapy water as well as with clear water, is exceptionally 15 well arranged so that the water strikes the dishes directly without missing any portions of the same, and at the same time is simple in construction and can be used as a kitchen table, when not used as a washing 20 machine.

The principles involved in my invention are embodied in the preferred washing machine shown in the accompanying drawing, in which Figure 1 is a perspective view of 25 my washing machine; Figure 2 a side view of the same, a portion of the front being broken away to disclose the interior; Figure 3 an enlarged detail view of a belt tightener; Figure 4 a cross section through 30 a tray along line 4-4 of Figure 5; Figure 5 a top plan view of the tray; Figure 6 a perspective view of a spoon holder, and Figure 7 a side view of a drum used in my device for agitating the water.

35 In detail the washing machine (1) comprises a preferably rectangular box (2) having two sides (3), two end pieces (4), a horizontal top (6) and a sloping bottom (7). A portion (8) of the top is stationary 40 and serves as support for the motor (9), while another portion (11) is hingedly connected to one of the sides, as shown at (12).

The sloping bottom provides a deep portion (14) in the box, which holds the agitating means for the water, and a shallow 45 portion (16) adapted to receive the dishes. The principal part of the latter portion is the tray (17), which is shown in detail in Figures 4 and 5 and is adapted to receive the 50 dishes and to be slid into the box, until it is stopped by the stop (18). This tray is an open, rather flat box, screened on the sides, as shown at (19), and provided on top with a plurality of wires (21) crossing the box 55 diagonally. These wires are provided for the support of the dishes which are placed

between the wires on edge and prevented from rolling by a plurality of cross wires (22). It will be seen that when the tray is placed inside the box, each one of the 60 dishes is disposed in such a manner as to present a slanting surface to a stream of water coming from the agitator. This tray is intended to take the plate shaped dishes, while for the cups I provide a plurality of 65 hooks (23) secured in one or both of the sides of the box. One corner (24) of the tray is left unoccupied by diagonal wires and provided with a screen at the bottom. This portion is reserved for the knives and 70 forks, while for the spoons I provide a special cylindrical receptacle (27) having as its principal features a base (28) and a vertical, cylinder-shaped body of wire netting for the support of the spoons. This holder 75 is placed in any convenient place where it will be struck by the water. The tray itself is preferably made sufficiently short to allow of a generous space rearwardly of the same for the reception of larger utensils as 80 pots and pans.

As agitating means I use a revolving drum (31) provided with a plurality of fans, preferably three. The drum is cylindrical in form and is slidably secured on 85 the shaft (33) supported in the sides of the box. It is prevented from rotating on the shaft by the bolts (34) extending diametrically through the shaft and the cylinder and secured by nuts (36). It will be noted that 90 the fans do not extend from the drum at the same angles, one of them, (37), extending radially, the second one, (38), at a small angle to the radius, and the third one, (39), at a larger angle to the radius. This arrangement is selected for the purpose of insuring a more thorough distribution of the 95 water over the dishes, it being well understood that each of these fans will throw the water in a different direction and cause the 100 same to strike the dishes at a different angle.

The cylinder is partly submerged in water as shown in Figure 2 and its rear portion is surrounded by a shield (41), so that when the drum is rotated clockwise the fans will 105 dip into the water and carry along a portion of the same between the drum and the shield, until after passing the upper end of the shield the water is released and free to follow the centrifugal force set up in the 110 same through the rotary motion as a consequence of which it will be hurled at the

2

dishes, rinse and clean the same, collect at the bottom, and due to the slope of the bottom return to the agitator to be again picked up by the fans. A special catch (42) is provided for the solid substances washed off the dishes, as tea or coffee grounds or remainders of food adhering to the plates. The catch is in direct communication with the outlet (43) of the washing machine, which is provided at the bottom near the lower end of the box. A trap (44) is provided in the outlet to prevent gases from rising through the same, a cap (46) of the usual form is provided, thus allowing the same to be drained. The outlet is controlled by a valve (47) which can be operated by means of the rod (48) from the top of the washing machine. A float (49) carrying a vertical rod (51) serves to indicate the level of the water in the washing machine. The water inlet is shown at (50).

The drum is rotated by means of the motor (9) secured on top of the washing machine, which engages through the belt (52) the wheel (53) keyed to the shaft (33) supporting the drum. In the machine I am using now the cylinder makes about 500 revolutions per minute and I prefer to provide special tightening means for the belt, as shown in detail in Figure 3. This means comprises an idler wheel (60) mounted on the transverse end (56) of the longitudinal shaft (57) so as to frictionally engage the outside of the belt (52). The shaft (57) is slidably mounted in a bracket (58) secured to the washing machine and caused by the spring (59) to draw the belt inwardly, thereby tightening the same.

In operation the dishes are assembled on

the tray in the manner described, the cups suspended, the forks and knives placed on the screen, the spoonholder placed in a convenient spot, the pots and pans assembled rearwardly of the tray, hot water poured into the box, soap or washing powder supplied, and the motor started. The fans then throw the water violently against the dishes from different directions and effect a thorough cleaning of all the contents of the box, the water returning over the bottom of the box so as not to in any way interfere with the water thrown by the fans and being agitated continuously. The solid substances washed from the dishes assemble in the catch (42) without further partaking of the agitation. When the dishes are clean the water is drained off, and clean water admitted to rinse the dishes.

The motor can be easily removed at any time and used for other purposes.

I claim:

A dishwashing machine comprising a water holding receptacle having a slanting bottom, means for securing dishes in the receptacle, a large drum adjacent one end of the receptacle having a plurality of straight fans emanating at different angles from its periphery for throwing the water from different directions into contact with the dishes, and a curved shield partially surrounding said drum for causing the water to be discharged from the upper portion thereof, said shield providing adjacent its lower portion an extended lip in spaced relation to the bottom of the receptacle to provide a trap for solid particles and a discharge outlet connected to said trap.

MELVILLE M. UTTERBACK.
